Primary Examiner — George D. Kirschbaum

Assistant Examiner — Patricia K. Beard

(57) **CLAIM**

The ornamental design for an ice skate blade, as shown and described.

DESCRIPTION

FIG. 1 is a perspective view of an ice skate blade according to the design;

FIG. 2 is a left view of the ice skate blade of FIG. 1;

FIG. 3 is a right view of the ice skate blade of FIG. 1;

FIG. 4 is a top view of the ice skate blade of FIG. 1;

FIG. 5 is a bottom view of the ice skate blade of FIG. 1;

FIG. 6 is a front view of the ice skate blade of FIG. 1; and,

FIG. 7 is a rear view of the ice skate blade of FIG. 1.

The broken lines do not form part of the design. The dash-dot-dot-dash lines represent the boundary of the claimed design.

1 Claim, 3 Drawing Sheets
